INVENTOR.

BY *Walter S. Neelheim*
ATTORNEY.

UNITED STATES PATENT OFFICE.

ALBERT W. MORSE, OF LONG ISLAND CITY, NEW YORK.

HAND-OPERATED PUMP.

Application filed September 6, 1922. Serial No. 586,490.

To all whom it may concern:

Be it known that I, ALBERT W. MORSE, a citizen of the United States, and a resident of Long Island City, in the county of Queens and State of New York, have invented certain new and useful Improvements in Hand-Operated Pumps, of which the following is a specification.

This invention relates to improvements in hand operated pumps, the kind in which a plunger is reciprocated within a barrel, by means of a usually T shaped handle attached to one end of the plunger rod.

One of the objects of the invention is to eliminate the pinching or bruising of the fingers of the operator when the pump is at the limit of its downward stroke.

Another object is to prevent the plunger striking the bottom of the pump at each downward stroke and causing undue vibration or bending of the plunger rod and other damages to the operating mechanism.

A still further object is to fasten the handle part proper to the plunger rod in a manner which is stronger than means heretofore employed and at the same time considerably less expensive.

The combination of these improvements results in a pump far superior to any now marketed, simpler in design and much stronger in construction.

The invention is illustrated in the accompanying drawings, which show a hand operated pump for inflating the tires of an automobile, and in which—

Fig. 1 is a sectional view of such a pump at the end of its downward stroke;

Fig. 2 is an enlarged fragmentary sectional view of the operating means of the pump; and

Fig. 3 is a longitudinal sectional view along the plane of line 3—3 in Fig. 2.

Like characters of reference denote similar parts throughout the several views and the following specification.

10 is a barrel of the pump. 11 is a plunger rod, its lower end attached to a plunger 12. 13 is a base to which is fastened the barrel 10. 14 is an air passage. Base 13 is provided with a boss 15 containing (not shown in detail) the customary air inlet passage and discharge check valve suitably connected to a rubber hose, adapted to be screwed or otherwise fastened to an automobile tire.

16 is a handle T, consisting of a tubular

ferrule 17 and a relatively long tubular shank 18. Shank 18 is screwed into ferrule 17 at right angles at 19.

20 is a handle piece having a somewhat enlarged central cylindrical portion at 21 which has a tight drive fit with the inner part of ferrule 17.

Handle part 21 is bored out transversely and shank 18 longitudinally to engage with a tight drive fit the plunger rod 11.

22 is a cap substantially cylindrical in shape, in screw threaded engagement at 23 with the upper end of pump barrel 10. 24 is a small tubular extension at the top of cap 22. 25 is an inner central tubular projection below the top of cap 22, and is bored out centrally to frictionally and slidingly engage the plunger rod 11.

In assembling, the shank 18 is screwed tightly into ferrule 17. Handle 16 is then forced into the ferrule until its cross bore is in central alignment with the center bore of shank 18. The plunger rod 11 is then forced into the bore of shank 18 and into the handle with a very tight driving fit, fastening the plunger rod and the handle rigidly together.

In the usual construction of the operating means of a tire pump, the plunger rod is generally threaded and screwed into the handle T, and very frequently works loose. In applicant's device, the plunger rod and handle are so rigidly fastened together by means of drive fits that these parts practically present one integral unit.

Furthermore, in the usual tire pump, the shank of the handle T being very short and the extension on top of cap 22 being relatively high, the operator invariably catches his fingers between the lower end of the shank and the cap when the plunger is at the limit of its downward stroke. Inspection of Fig. 1 clearly discloses the fact that it is impossible to bruise or pinch one's fingers since owing to the relatively long shank (about twice its outside diameter) there is plenty of clearance between the operator's hand and the top of cap 22, when the lower end of shank 18 is limited in its downstroke by small extension 24. In this position there is a clearance between the plunger 12 and the base of the pump, so that no strain whatever is exerted against the lower end of the plunger rod, except the resistance of the air, which clearance is instrumental in eliminating undue strains on the rod.

With the operating parts constructed as

disclosed by applicant, the handle ferrule and the shank may be made of tube stock or solid bar, and the cap 22 may be made of solid bar stock with the least possible amount of waste due to the guide or extension 25 being at the inside of the cap, all of which result in a pump which is of simple design, strong in construction and most economical in manufacture.

10 What I claim as new, is:

1. In a pump of the character described, a handle, a handle ferrule fitting tightly over the said handle, a tubular shank screwed at right angles into the said handle ferrule, and 15 a plunger rod having a tight drive fit with the inner diameter of the said tubular shank and also being driven tightly into the said handle, the said shank being in length approximately twice its outside diameter.
2. In a pump of the character described, a handle, a tubular handle ferrule fitting tightly over the said handle, a tubular shank being in length approximately twice its outside diameter, screwed tightly into the said handle ferrule, a plunger rod having a tight drive fit with the inner part of the said tubular shank and also being driven tightly into the said handle, and a cap having an inner tubular extension in sliding engagement with the 30 said plunger rod.
3. In a pump of the character described, a handle, a tubular ferrule fitting tightly over the said handle, a tubular shank being in length approximately twice its outside

diameter, screwed tightly into the said ferrule, a plunger rod having a tight drive fit with the inner part of the said tubular shank and also being driven tightly into the said handle, and a cap having an inner tubular extension in sliding engagement with the 40 said plunger rod, the downward stroke of the said plunger rod being terminated by contact of the said shank with the said cap.

4. In a hand operated pump of the reciprocating kind, a handle, a tubular ferrule fitting tightly over the said handle, a tubular shank screwed tightly into the said ferrule, a plunger rod having a tight drive fit with the inner part of the said tubular shank and 50 also being driven tightly into the said handle, and a cap having an inner tubular extension in sliding engagement with the said plunger rod, the downward stroke of the said plunger rod being terminated by contact 55 of the said shank with the said cap, the said shank being of a length sufficient to prevent the pinching of an operator's fingers when the plunger rod is at the end of its downward stroke.

In testimony whereof I have hereunto set my hand and seal in presence of two subscribing witnesses.

ALBERT W. MORSE. [L. S.]
